E. W. KELLY,
ELECTRICAL VACUUM DISCHARGE DEVICE.
APPLICATION FILED OCT. 6, 1919.

1,414,741.

Patented May 2, 1922.

Inventor:
Edwin W. Kelly,
By appointment, Sec. Chittenden Miles,
Attleson

UNITED STATES PATENT OFFICE.

EDWIN W. KELLY, OF OAK PARK, ILLINOIS, ASSIGNOR, BY MESNE ASSIGNMENTS, TO VICTOR X-RAY CORPORATION, OF CHICAGO, ILLINOIS, A CORPORATION OF NEW YORK.

ELECTRICAL VACUUM DISCHARGE DEVICE.

1,414,741.

Specification of Letters Patent. Patented May 2, 1922.

Application filed October 6, 1919. Serial No. 368,628.

To all whom it may concern:

Be it known that I, EDWIN W. KELLY, a citizen of the United States, residing at Oak Park, in the county of Cook and State of Illinois, have invented a new and useful Improvement in Electrical Vacuum Discharge Devices, of which the following is a specification.

My invention relates to electrical vacuum discharge devices and my primary object, generally stated, is to provide, by a novel, simple and economical means, for the steady operation of such devices with a comparatively uniform electrical resistance and the elimination of the high break-down electrical resistance of the vacuum.

More specifically, my invention relates, but not in any sense exclusively, to X-ray tubes which in accordance with the usual practice are provided with what are commonly known as bi-anodes, assistant anodes, auxiliary anodes, or designated by some other term which distinguishes them from the main anodes, and which in the following description are referred to as bi-anodes, the purpose of the bi-anode of an X-ray tube being to eliminate the high break-down electrical resistance of the vacuum and cause the tube to operate steadily with a comparatively uniform electrical resistance.

It has been the usual practice in the manufacture of X-ray tubes with bi-anodes, to form an opening in the enclosing insulating shell of the tube at a point remote from the cathode and approximating the region of the anode, and securing therein to be in communication with both the interior and exterior of the shell, a current conducting member.

The provision of the bi-anode as set forth presents a number of disadvantages, one of which is the necessity for the provision of the opening therefor in the enclosing shell of the tube, which requires the provision of a seal at this point and the attachment of a tubular extension, with consequent added expense in the production of the tube and likelihood of greater service required in maintaining the tube in operation. Furthermore, the communication of the bi-anode with the interior of the shell, and thereby its contact with the gas in the tube, affects the gas in the tube in such a manner, and beyond the control of the operator, as to cause the pene-

trating quality of the X-rays emitted from the tube to vary. Also the bi-anode presents a protuberance on the tube so located that it interferes, to a moderate extent under certain conditions, with the use of the apparatus in connection with other devices. Again the bi-anode is usually connected with the main anode by a spiral current-conducting member which presents interference in clamping the tube.

In connection with X-ray tubes my object is to provide for the elimination of the high break-down electrical resistance of the vacuum and cause the tube to operate steadily with a comparatively uniform electrical resistance, by means which will be free of the objections incident to the use of the bi-anode as commonly provided, as above pointed out, thereby to avoid the provision of an opening and seal therefor in the tube shell for such bi-anode and the reduction of the amount of service required in maintaining the tube in operation; to avoid a protuberance such as that above referred to; to avoid contact of the gas in the tube with the bi-anode and maintain more nearly constant the penetrating quality of the X-rays emitted from the tube; and other objects as will be understood from the following description.

Referring to the accompanying drawings, wherein I have illustrated my invention as applied to an X-ray tube, Figure 1 shows by a plan view an X-ray tube constituting a desirable embodiment of my invention. Figure 2 is an enlarged broken section taken at the line 2 on Figure 1 and viewed in the direction of the arrow, the main anode being shown in elevation. Figure 3 is a view of one end of the blank from which the bi-anode of the tube is formed; and Figure 4, an end view of the bi-anode bent to shape.

It may be stated as a preface to the following description of the preferred illustrated embodiment of my invention, that it is based upon the discovery that in order to perform the function of a conventional bi-anode, it is not necessary to provide an additional terminal exterior of the enclosing shell of the tube in metallic conductive relation to a terminal within the shell, but that this function may be performed by charging the outside surface of the insulat-

ing shell of the tube with the same electrical polarity, and preferably approximately the same potential as that of the anode. This may be accomplished in a large variety of ways, one way being illustrated in the drawings, and involving a member 5 of electric current-conducting material, as for example metal, preferably sheet metal, which is mounted upon the "anode-surrounding" extension 6 of the enclosing shell or bulb of the tube, this member preferably surrounding the extension 6. The end of the member 5 adjacent the bulb 7 is formed preferably with a plurality of divergent arms 8 which preferably are curved to correspond with the curvature of the portion of the bulb 7 which they oppose and with which they preferably, though not necessarily, contact. The opposite end of the member 5 bears such relation to a portion of the conductor through which the current is conducted to the main anode, represented at 9, that the member 5 is in intimate static inductive relation to the main anode 9, the member 5 in the construction shown and by preference, being in contact with the conductor referred to, which latter in the conventional form of the X-ray tube shown in the drawing, so far as the cathode 16, regulator 17, main anode and its electrical connection is concerned, is a cap 10 of current-conducting material connected with the current-conducting wire 11 leading to the anode 9 and electrically connected with the ring 12 on the cap 10 at which ring one of the terminals (not shown) of the high potential current for operating the tube would be connected or, if desired, the high potential wire may connect with any portion of the member 5 as desired.

In the particular construction shown, the member 5 is formed from a blank of sheet metal presenting a substantially rectangular portion 13, shown partly broken away in Fig. 3, of a length slightly less than the length of the extension 6 and of a width slightly less than the circumference of this extension, the portion 13 being provided at one end with the divergent arms 8 and at its opposite end with a tongue 14 terminating in a ring 15, which is bent to the position shown in Fig. 2 and receives the cap 10, thereby electrically connecting the member 5 with this cap.

While the bi-anode is by preference provided as illustrated and described, it need not, to carry out my invention, be so provided. The bi-anode may take any desirable form. It need not be in contact with the bulb, neither is it necessary that it be physically continuous, as for example where it is provided by applying to the bulb a paint containing current-conducting particles; nor need it be in actual physical contact with the anode terminal; nor is it necessary that it occupy substantially the relation shown

in the drawings relative to the main anode. It may approach the cathode end of the tube provided it is not located so close to the latter that sparking such as will render the tube inoperative, will occur between the region of the cathode and the bi-anode at such potentials as are used in common practice with the voltage upon which the apparatus may have been designed to operate, though it is preferred that it be so located that no sparking between it and the cathode region will occur. Furthermore, the bi-anode in accordance with my invention need not be in the nature of a branch from the main anode circuit, as in the case in the drawings shown, but may be a deflected portion of the anode portion of the circuit. While it is preferred that the charge supplied to the exterior of the bulb be of approximately the same potential as that of the anode, this is not necessary.

Examples of other kinds of devices to which my invention relates are various vacuum amplifying, modulating and oscillation-generating devices, such as the audion, etc.

What I claim as new and desire to secure by Letters Patent is:

1. An electrical vacuum discharge device comprising, in combination, its insulating enclosing shell, containing a cathode and an anode, the latter extending through a tubular extension on said shell, and means supported on said extension and located wholly exterior of said shell and approximating the anode for charging the exterior of said shell with the same polarity, and unchanging, as that of the anode, said means being located at such distance from the cathode as to have no major influence on the radiation from said cathode.

2. An X-ray tube comprising, in combination, its insulating enclosing shell containing a cathode and an anode, the latter extending through a tubular extension on said shell, and means supported on said extension and located wholly exterior of said shell and approximating the anode for charging the exterior of said shell with the same polarity as that of the anode.

3. An electrical vacuum discharge device comprising, in combination, its insulating enclosing shell containing a cathode and an anode, and means including an arm which extends along and is in close proximity to said shell, located wholly exterior of said shell, and approximating the anode for charging the exterior of the shell with the same polarity as that of the anode.

4. An X-ray tube comprising, in combination, its insulating enclosing shell containing a cathode and an anode, and a member of current-conducting material mounted on said tube and in electrical conductive relation to the anode portion of said tube, said

member being located wholly exterior of said shell, a portion of said member extending into such position as to cause the exterior surface of said shell, when the tube is 5 energized, to be charged with the same polarity as that of the anode.

5. An electrical vacuum discharge device comprising, in combination, its insulating enclosing shell containing a cathode and an 10 anode, the latter located in a tubular extension on said shell, and a member of current-conducting material having a hollow portion at which it engages said extension and provided with an arm which extends adjacent

said shell, said member being in electrical 15 conductive relation to said anode.

6. An electrical vacuum discharge device comprising, in combination, its insulating enclosing shell containing a cathode and an 20 anode, the latter located in a tubular extension on said shell, and a member of current-conducting material having a hollow portion at which it engages said extension and provided with diverging arms which extend adjacent 25 said shell, said member being in electrical conductive relation to said anode.

EDWIN W. KELLY.
